COLLAR STIFFENER

John Esposito, Brooklyn, N. Y.

Application August 15, 1932, Serial No. 628,923

1 Claim. (Cl. 2—132)

This invention relates to means for stiffening a soft collar so as to keep the same in proper shape and to prevent the points from turning upwardly, the general object of the invention being to provide a pair of members formed of celluloid or the like which are adapted to be placed within the outer flap of the collar through suitable openings formed in the under part of said outer flap.

10 The invention also consists in certain other features of construction and in the combination and arrangement of the several parts to be hereinafter fully described, illustrated in the accompanying drawing and specifically pointed out in 15 the appended claim.

In describing the invention in detail, reference will be had to the accompanying drawing wherein like characters denote like or corresponding parts throughout the several views, and in 20 which:—

Figure 1 is a view of a collar with the outer flap turned up to show the openings through which the stiffening members are placed to lie within a space formed between the outer part 25 of the flap and its lining.

Fig. 2 is a view of one of the stiffening members.

Fig. 3 is a section on line 3—3 of Fig. 1.

Fig. 4 is a perspective view of a collar having the stiffening members therein.

30 The drawing shows the invention in use with a detachable collar, but it will of course be understood that the invention can be used with a collar attached to a shirt.

As shown in Figs. 1 and 3, the outer flap A 35 of the collar is provided with a lining 1 which covers the entire inner face of the flap and is so sewn thereto as to leave a space between itself and the outer part of the flap. A diagonally arranged opening 2 is formed in the lining adjacent each end of the flap and these openings communicate with the space between the flap and its lining. I provide a pair of stiffening members 3 which are preferably formed of celluloid and each member is of substantially the 45 shape shown in Fig. 2, with an elongated substantially straight major portion but having one end provided with a pointed enlargement 4, which fits in the points or tips of the upper flap of the collar. Of course this enlargement will be made 50 to conform to the tip of the particular collar in which it is to be placed.

Each stiffening member is placed through one of the openings 2 with its small end passing towards the middle of the flap and then the enlarged end is placed in the tip or point of the upper flap and when the two members are put in place, they will stiffen the upper flap and hold it in its proper shape, keeping the points from turning upwardly and also enabling the collar to be worn in hot weather with but little danger of wilting. By reference to Figure 1 it will be 10 noted that the openings 2 extend across the broad portions of the points or tips of the collar; also, that the said openings 2 are gradually reduced in width from their transverse centers to their ends. By virtue of this, the stiffening members 3 may 15 be readily introduced between the flap and the lining in the manner before explicitly described, and when the stiffening members are in proper working position there is no liability of either stiffening member being casually displaced.

20 It is thought from the foregoing description that the advantages and novel features of the invention will be readily apparent.

It is to be understood that changes may be 25 made in the construction and in the combination and arrangement of the several parts provided that such changes fall within the scope of the appended claim.

Having thus described my invention, what I 30 claim as new is:—

The collar described consisting essentially of a band and a flap attached to the upper edge of the band, said flap having pointed tips at its ends, a lining corresponding in area with and attached to the flap and forming a space between itself and said flap, said lining having across the inner portions of the pointed tips slots disposed at acute angles to the line on which the flap is attached to the upper edge of the band, said slots being gradually reduced in width from their 35 transverse centers to their ends, and stiffening members of flat flexible material inserted endwise inwardly through said slots into the space between the flap and its lining, each stiffening member having a pointed enlargement at its 40 outer end sheathed in and conforming to and fully occupying the portion of the flap outwardly beyond the adjacent slot.

JOHN ESPOSITO. 50
